UNITED STATES PATENT OFFICE.

NICHOLAS W. AKIMOFF, OF PHILADELPHIA, PENNSYLVANIA.

PROPELLER APPENDAGE.

Application filed January 15, 1924. Serial No. 686,410.

To all whom it may concern:

Be it known that I, NICHOLAS W. AKIMOFF, citizen of the United States, residing at Philadelphia, in the county of Philadelphia and State of Pennsylvania, have invented certain new and useful Improvements in Propeller Appendages, of which the following is a specification.

This invention relates to appendages for propellers and apparatus associated therewith, whereby the circulation about the propeller may be positively increased or varied as desired.

In accordance with the principles of modern hydrodynamics, the action of a theoretically perfect propeller is controlled by a central vortex aft of the propeller, and resulting from the combined advance and rotation of the propeller, which is fed either positively or negatively by fractional vortices corresponding to each blade. Thus the greater the activity of the central core vortex the greater the circulation about each blade, as the circulation about the blades is intimately linked with that of the central vortex. Obviously, advantages arise from this increased circulation such as greater thrust of the propeller and less danger of cavitation thereof in operation and, so too, this increase in circulation, properly controlled, affords means to regulate the propeller action and speed thereof within certain limits due to loading characteristics and the like.

Propeller appendages have been heretofore in use which rotate with the propeller and increase the circulation of the central vortex by the action of the friction or viscosity of the water or air thereon. Other types of appendages have been devised which, driven independently of the propeller and at varying and different speeds therefor, strengthen and control the central vortex associated with the propeller and result in a corresponding increase and control of the circulation about the propeller.

In the present invention, I aim to provide an appendage for propellers which increases by a suction action the circulation of the central vortex associated with the propeller and which thereby increases also the circulation about each propeller blade, the sum of which circulations is substantially approximate to that of the central vortex.

A further object is to provide an appendage for propellers and associated apparatus

which, by maintaining a suction or vacuum therewith, operates to regulate the action of the propeller by controlling the circulation of the central vortex associated therewith. 60

A further object is to provide an appendage of the above type for screw propellers by which the circulation of the central vortex from the propeller may be increased or diminished within certain limits and the corresponding speed of the propeller varied within these limits. 65

A further object is to provide a device of the above mentioned character in which the central vortex associated with said propeller is increased by suction acting on the vortex associated with said propeller. 70

A further object of my invention is to provide an appendage and suction apparatus associated therewith, operating with a propeller whereby the circulation of the medium about said propeller may be varied by varying the suction acting on said appendage. 75

A further object is to provide an appendage for propellers and apparatus associated therewith attaining the objects stated above which is simple, reliable and efficient in operation and which may be installed with various types of propellers and at a minimum cost. 80

Other objects of the invention than those stated above, together with the advantages inherent therein, will be in part obvious and in part specifically referred to in the course of the following description of the various elements, arrangement of parts, combinations thereof, and application of principles constituting the invention; and the scope of protection contemplated will appear from the claims. 95

In the accompanying drawings, which are to be taken as part of the specification and in which I have shown the preferred form or embodiment of my invention—

Figure 1 is an elevation, partly in section, of the appendage and associated device applied to a boat or ship; and 100

Figure 2 is an enlarged section of certain parts as shown in Figure 1.

Referring now to the drawings and more particularly to Figure 1, 10 designates the rear end of the hull of a boat adapted to be driven by a propeller 11 of the usual design mounted on a drive shaft 12 driven by any motive means (not shown). Mounted 105 on the hub of the propeller 11 by any suitable means, such as by bolts, and rear-

wardly thereof, is an appendage 13 so positioned as to be located, in reality, in the core of the vortex associated with the propeller while in motion. The appendage 13 is cast hollow, but is closed at its aft end and is provided with a plurality of longitudinal slots 14, say, twelve in number. These slots 14 thus render the hollow appendage 13 open to the surrounding medium, 10 such as water, as in the present case.

The drive shaft 12 is hollow for a portion of its length from its rear end frontwardly and has its aft end open to the hollow appendage 13, so that the surrounding water may flow through the slots 14 into the interior of the appendage 13 and through the hollow drive shaft 12. Positioned inside of the boat in any convenient location, and surrounding the drive shaft, is a suction chamber 16 provided with stuffing boxes 17 and packing 18 whereby a vacuum set up therein can be maintained air and water tight. A series of openings 20 are provided in the portion of the shaft 25 12 surrounded by the chamber 16, serving as passageways from the hollow bore thereof to the suction chamber 16. A vacuum is maintained in the chamber 16 by any desirable means as by a vacuum tank 21, which 30 is united thereto by the connecting pipe 22. A discharge outlet is provided in the tank 21 and includes a pipe 23 leading to a discharge nozzle or valve 24 whereby an excess of water in the suction tank 21 may be 35 discharged overboard, or inboard, for any purpose desired. A valve 25 is provided in the pipe line 22 adjacent the suction chamber 16 whereby the amount of vacuum in the chamber 16 may be readily controlled. For 40 the purpose of cleansing or blowing out any dirt or matter which accumulates in the tank 16, an air compressor 26 is provided adjacent the chamber 16 and compressed air may be led thereto through the 45 pipe line 27.

The operation of the device is, of course, obvious from the above. A vacuum set up in the chamber 16 through the medium of the vacuum tank 21 causes the water surrounding the appendage 13 and propeller 11 respectively to be drawn into the appendage through the slots 14 and through the hollow shaft 12 to the chamber 16 and through the vacuum tank 21 and discharged 50 therefrom. Upon rotation of the propeller 11, a central vortex resulting from its rotation and advance, is set up which, by the action of the appendage rotating with the propeller and the suction means hereinbefore described, acting thereon, is materially strengthened and the circulation about the propeller as a whole is consequently materially increased. The valve 25 provides 55 a ready and efficient means for controlling the suction in the system with the

corresponding control of the increase or decrease of the circulation set up. A pump or siphon might also be efficiently used to create a vacuum in the chamber 16, and such is sought to be comprehended by my 70 invention.

Inasmuch as many changes could be made in the above construction and many apparently widely different embodiments of my 75 invention could be made without departing from the scope thereof, it is intended that all matter contained in the above description or shown in the accompanying drawings shall be interpreted as illustrative and 80 not in a limiting sense.

It is also to be understood that the language used in the following claims is intended to cover all of the generic and specific features of the invention herein described and all statements of the scope of the invention which, as a matter of fact, may be said to fall therebetween.

I claim:

1. In combination with a propeller and an appendage therefor, suction means operative to induce increased circulation of the central vortex associated with said propeller.
2. In combination with a propeller, means rotatable therewith operative to increase the circulation of the central vortex associated with said propeller, said means comprising a hollow member rearwardly of said propeller, adapted to exert a vacuum on the surrounding medium.
3. In combination with a propeller, means operative to induce increased circulation of the central vortex associated with said propeller, said means comprising an appendage axially mounted with relation to said propeller, and means adapted to exert suction on the water surrounding said appendage.
4. In combination with a propeller, a drive shaft upon which said propeller is mounted, hollow throughout a portion of its length, an appendage mounted on said drive shaft rearwardly of said propeller and being open to the surrounding medium; and means adapted to exert a suction pressure through said drive shaft and appendage upon the surrounding medium.
5. In combination with a propeller, a main shaft hollow for a portion of its length, upon which said propeller is mounted, a hollow appendage mounted on said main shaft rearwardly of said propeller, said appendage having longitudinal slots therein, and means adapted to exert a suction through said drive shaft and appendage upon the surrounding medium whereby to increase the circulation about said propeller.
6. In combination with a propeller, a main drive shaft upon which said propeller is mounted, a hollow appendage mounted on said propeller and rearwardly thereof, said appendage having longitudinal slots

therein, said drive shaft being hollow for a portion of its length, and means to exert a suction action through said drive shaft and appendage upon the surrounding medium whereby to increase the circulation about said propeller, and means operative to vary the suction pressure through said drive shaft and said appendage.

7. In combination with a propeller, a main drive shaft upon which said propeller is mounted, a hollow appendage mounted on said propeller and rearwardly thereof, said appendage having longitudinal slots therein, said drive shaft being hollow for a portion 15 of its length, a chamber surrounding said shaft, passageways leading from the hollow portion of said shaft to said chamber, means to create a vacuum in said chamber, whereby such vacuum is transmitted to the water surrounding said appendage through said drive shaft, means to vary the vacuum set 20 up in said chamber as desired, and means to clean said chamber.

8. In combination with a propeller and an appendage therefor, suction means operative through said appendage to induce increased 25 circulation of the central vortex associated with said propeller.

9. In combination with a propeller and an appendage therefor, suction means operative through said appendage to induce increased 30 circulation of the central vortex associated with said propeller.

In witness whereof I have hereunto signed my name.

NICHOLAS W. AKIMOFF.
